UNITED STATES PATENT OFFICE

AINSLIE T. CARTER, OF COLDWATER, NEW YORK, ASSIGNOR TO GENERAL RAILWAY SIGNAL COMPANY, OF ROCHESTER, NEW YORK

FOCUSING DEVICE FOR LIGHT SIGNALS

Application filed August 25, 1926. Serial No. 131,467.

This invention relates to light signals for railway signaling purposes, and more particularly to a device for making it easy to determine when a lamp has been properly 5 adjusted to have its filament on focus.

In the typical light signal, an incandescent lamp with a concentrated filament is used in combination with a lens, a mirror, or other suitable light projecting means to project a 10 light beam of limited spread to give a signal indication, either by virtue of its color or association with other beams of light. In order to obtain the desired range and spread, it is essential that the filament of the incandescent lamp be located accurately at the 15 focal point of the light projecting unit. Incandescent lamps, as ordinarily manufactured, have some variation in the location of the filament to a lamp base, so that when 20 a new lamp is put in a light signal, the filament will rarely come at the exact focal point. To take care of these variations, it has been proposed to make the lamp socket adjustable in the signal, so that an adjustment 25 may be made to bring the filaments of the different lamps at the right point; and in order that this adjustment may be made accurately and readily, it is desirable to provide means for determining when the filament 30 of a given lamp is on focus.

In accordance with the present invention it is proposed to provide sighting or finding devices which will indicate when the filament of the lamp has been adjusted to the right point. One object of the invention is to make such finders of a simple construction so that they may be cheaply manufactured and permanently installed as a part of each signal. Another object is to provide 35 a finder which may be easily adjusted during the process of assembling the signal, so that the finders will define the right point for the location of the lamp filament for that particular signal, independently of accuracy of machining the various parts. A still further object is to arrange the lines of sight defined by the finders with relation to the lines of movement of the socket as it is adjusted so as to facilitate the adjustment of 40 the socket.

Further objects and advantages of the invention will be in part apparent and in part pointed out as the description progresses.

In the accompanying drawings, Fig. 1 55 shows a vertical section through a light signal embodying the invention, said section being transversely of the axis of the light projection unit and taken on the line 1-1 in Fig. 2;

Fig. 2 shows another vertical section through the signal on the axis of the lens;

Fig. 3 shows a longitudinal section through one of the finders;

Fig. 4 is an end view of the finder; and 65

Fig. 5 is a transverse section through the finder on the line 5-5 in Fig. 3.

While the invention may be applied to light signals of various types, it has been shown in the drawings in connection with a 70 single light projecting unit employing the well known doublet lens combination. This unit shown is capable of emitting only one beam of light of a particular color, and in practice would be combined with the other light units giving other distinctive colors; or several like units would be disposed in a 75 predetermined relation so as to give an indication by the disposition or arrangement of the lights of the same or different colors. 80 The various details and characteristics of the light signal itself are not material to the present invention; and the particular form shown is merely representative.

The signal unit illustrated comprises a box-like casing 1, having its back closed by a swinging door 2 which is provided with the usual gaskets, ventilator, hinges and fasteners. The casing 1 is formed with openings 3 85 at the top and bottom. The bottom opening 3 receives a rounded projecting lug on the supporting bracket B, so as to form a ball and socket connection; and the casing 1 is secured to this bracket by bolts 4. The bracket B in turn is supported on a suitable 90 pole 5, or the like, being adjustable thereon and held in place by screws 6. The opening 3 at the top, together with the similar opening in the bottom of the next casing superimposed 95 on the one shown, provides a convenient pas- 100

sage for wires; but since only one casing is illustrated, this top opening is covered by a cover plate 7. To the front wall of the casing 1 is secured the usual hood 8.

5 The inner and outer lenses 9 and 10 of the usual and well known doublet lens combination, are held by gaskets and bezel rings in the usual way in a tapered lens barrel 11 which is secured in an opening in the front 10 wall of the casing 1 by bolts 12. The inner bezel ring 13, retaining the inner lens in place, is formed of an inverted U-shape, as shown in Fig. 1, and adjustably supports the lamp and the sighting device or finders of 15 this invention.

Referring first to the adjustable support for the socket 14 for the lamp 15, this socket may be of any suitable construction, either a screw socket or a bayonet type socket; and the block of insulating material, to which the socket shell is fastened, is secured to a shelf-like member 16 by bolts 17 passing through transverse slots in said member 16, so that the socket may be moved forward 25 and back on lines substantially parallel with the axis of the lens. Upturned flanges at the ends of the member 16 are fastened by bolts 18 to the lower ends of the inner bezel ring 13, said bezel ring being formed with vertical slots 19 (see Fig. 1) through which said bolts 18 pass, and the upturned flanges of the member 16 being formed with horizontal slots 20 for said bolts. Thus, the shelf 16 may be moved up and down or sideways 35 with relation to the axis of the lens. This way of supporting the socket 14 permits the lamp to be moved in and out, sideways in either direction, or up and down, with respect to the axis of the lens, in any one of three 40 directions approximately at right angles. It should be understood that this adjustable support for the socket is merely illustrative, and that various other adjustable supports permitting adjustment in these or similar directions may be employed in connection with the 45 finders or sighting devices about to be described.

The incandescent lamp 15 is of any suitable construction, with a concentrated single 50 or double filament located with respect to its base with the usual manufacturing inaccuracies.

The finders, designated as a whole F, are fastened to the inner bezel ring 13 to provide 55 lines of sight substantially at right angles to each other and parallel with the directions in which the socket may be adjusted up or down and sidewise. Referring particularly to Figs. 3, 4 and 5, each finder comprises a 60 base 22, with holes for the screws 23 fastening the finder to the bezel ring. To this base 22 is fastened a tubular extension 24, having a V-shaped notch designated 25 cut in one side. This tubular extension 24 may be secured 65 to the base 22 in any suitable manner

by soldering, sweating in, or spinning. The outer end of the tubular extension 24 is formed with a longitudinal slot 26 (see Fig. 5), for the purpose hereinafter explained. The tubular extension 24 supports the tube 27 constituting the sighting device or finder proper.

70 The outer end of this sighting tube 27 is covered by a piece of ground glass 28 held in place by a ring 29, soldered or otherwise 75 suitably secured to the end of the tube. On this ground glass is placed suitable point designating marks, such as the cross hairs 30 (see Fig. 4), although spots, small rings, or the like may be employed. At an intermediate point in the length of the sighting 80 tube is a partition 31 with a central small pin hole 32. To fasten this partition 31 in place, the tube 27 is preferably slotted transversely about half-way down, and the partition inserted and sweated or soldered in place. This partition 31 is preferably made as thin as practicable, and the hole 32 relatively 85 small so as to form an efficient light directing means. The inner end of the tube 27 is formed with a V-shaped slot; and a plate 33, inclined at about 45 degrees to the axis of the tube, is secured by solder or the like to the tube at one edge of this opening, as shown in Fig. 3. To this plate 33 is secured a small 90 mirror 34. As shown, small retaining ears are pressed out of the plate 33 and bent down over the edge of the mirror 34 to hold it in place.

95 Since small inaccuracies in the location and size of holes, alignment of finished surfaces, and the like, are unavoidable in practical manufacture, it is not expedient to attempt to make the finders F and assemble them on the bezel ring 13 with the expectation that they will accurately define a particular point 100 with reference to the bezel ring. Also, small variations in the lenses themselves, and in their supporting elements, prevent the correct focal point for a given lens combination 105 always being at a fixed space relation to the inner bezel ring 13. Consequently, in practicing this invention, it is proposed to 110 assemble the parts as they happen to come, put a light in the socket and light it, and then 115 adjust the socket, irrespective of the finders F, until the filament of the lamp is at the correct point to give a beam of the desired 120 intensity and spread. This condition is obtained by direct observation of the beam of light itself; and while this may be done by 125 viewing the signal from a distance, the adjustment of the lamp socket to put the filament on focus is preferably made in a darkened room, in which there is a screen with 130 marks thereon to define the proper size of the beam for the selected distance between the signal and the screen.

135 Having determined in this way the proper point for the filament of that particular sig-

nal, the problem is to have the finders F define that particular point, so that the filaments of other lamps may be adjusted to that same point and be focused for the most efficient beam for that particular signal. With the filament lighted, its image is reflected by the mirror 34 of each finder F through the pin hole 32, which has the effect of a lens, and onto an image receptive surface in the form of ground glass 28. The image of the filament is sharply defined on the ground glass 28, and is larger or smaller than the actual image, depending upon the comparative distances between the pin hole 32, which acts as a light directing device somewhat similar to a lens, and the mirror 34, and ground glass 28. In short, for a given mark on the ground glass, each finder accurately defines a sighting line.

While the finders may be made to define the point at which a properly focused filament is located by putting the cross hairs on the ground to mark the point where the image actually comes after the assembly and the focusing operation just explained, the various inaccuracies might bring such marks on the ground glass off to one side, limiting the field of the finder; and rather than correct the inaccuracy in the construction and location of the finders by marking the cross hairs in the right place it is preferred to make the finder proper, including the mirror, pin hole, and ground glass, adjustable on its support. In the particular construction shown, the tube 27, when first assembled, may be moved in or out, or turned; and by these movements it is possible to bring the image on the cross hairs 30. The tube 27 is then permanently secured to its supporting base 22 by running solder into the slot 26 in the tubular extension 24. In this way, the finders may be readily adjusted in spite of inaccuracies in the manufacture and assembly of the parts, and after adjustment may be permanently fixed in position for the particular signal. This procedure of determining the focal point of a signal by actual inspection, and adjusting and fastening the finders in position to define the correct focal point can be easily performed by ordinary labor, and is more economical and efficient than attempting to use special manufacturing expedients to obtain uniform and accurate space relation of the parts.

Whenever a new lamp is placed in the socket and lighted, if the images of its filament fail to come at the proper points on the ground glass 28 of each finder, the socket is then adjusted in or out, up or down, or sideways, as the case may be, to bring the filament of that particular new lamp at the right point prescribed by the finders.

The finders F afford two lines of sight intersecting at right angles in a common plane; and these lines of sight are made parallel

with the directions in which the socket and the lamp filament move as the socket is adjusted up and down or sideways in said plane. After the socket has been moved in or out along the axis of the lens to bring the lamp filament in the common plane of the lines of sight of the finders, then the adjustments up and down and sideways may be made independently with reference to each finder in turn, thereby greatly facilitating the positioning of the lamp in the right place.

The finders F show the area and to a degree the intensity of the lamp filament as it is actually lighted, so that the adjustment may be made to dispose the filament with reference to the exact focal point so as to obtain the greatest efficiency from the filament. The images of the filament stand out clearly on the ground glasses of the finders, even in daylight, and in a position where they can be easily observed while adjusting the lamp, so that the procedure of adjusting a lamp is carried out to much better advantage than if the operator had to peep through a sighting opening. Various other practical advantages of the filament sighting arrangement of this invention will be apparent to those skilled in the art.

While the invention has been described with reference to one specific construction and arrangement of parts, I desire to have it understood that this construction is susceptible of various adaptations and modifications without departing from the functions and principles characterizing the invention.

What I claim is:—

1. Focusing means for lamps for light signals comprising, in combination with a lens and a support bearing a fixed relation thereto, a lamp socket adjustably attached to said support for independent movement in three directions substantially at right angles to each other, one direction being along the axis of said lens, two like optical finders each comprising a telescopically related base and sighting tube, each sighting tube having a mirror directly exposed to light from a lamp in said socket and an image receptive surface with point identifying marks thereon, and means permanently securing the bases of said finders to said support with the axes of their sighting tubes parallel with the axis of the lens and separated substantially 90 degrees in a plane transverse to said axis.

2. In a light signal, the combination with a lens and an adjustable lamp support, of an optical device for indicating when a lighted filament of a lamp in said socket lies in a sighting line, said optical device comprising a tube disposed with its axis substantially parallel to the axis of the lens, a mirror at one end of the tube inclined substantially 45 degrees to its axis, and directly exposed to light from a lamp in said socket, means at the other end of said tube constituting an

image receptive surface having point identifying marks thereon, means in the tube for projecting an image of a lighted filament reflected from the mirror onto said receptive surface, a base supporting said tube, and means fixing the base with respect to said optical device.

3. In a light signal, a lens, a retaining ring bearing against the inside edge of said lens, a lamp and socket therefor disposed with their axes transverse to the axis of the lens and adjustably supported by said ring to move in three directions substantially at right angles to each other, one of said directions being substantially parallel to the axis of the lens, two finders of the same construction fixed to said ring substantially 90 degrees apart and defining sighting lines parallel with said two directions in which said lamp socket may be moved transversely to the axis of said lens, each finder comprising a base fastened to the ring and a tube received in said base for movement along and about the axis of said tube, a mirror near the end of each tube inclined substantially 45 degrees to its axis, a ground glass with point identifying marks thereon at the other end of said tube, means in said tube for projecting the image of a lighted filament reflected from said mirror onto said ground glass, said tubes extending substantially parallel with the axis of the lens and having their ground glasses both visible at the same time from the rear of the signal.

35. In testimony whereof I hereby affix my signature.

AINSLIE T. CARTER.
